UNITED STATES PATENT OFFICE.

HARRY B. SNYDER, OF DENVER, COLORADO.

DESIGN FOR A CANE.

SPECIFICATION forming part of Design No. 20,991, dated August 11, 1891.

Application filed June 1, 1891. Serial No. 394,794. Term of patent 3½ years.

To all whom it may concern:

Be it known that I, HARRY B. SNYDER, a citizen of the United States of America, residing at Denver, in the county of Arapahoe and State of Colorado, have invented a Design for Cane-Heads; and I do declare the following to be a full, clear, and exact description of the invention, such as will enable others skilled in the art to which it appertains to make and use the same, reference being had to the accompanying drawings, and to the letters of reference marked thereon, which form a part of this specification.

In the accompanying drawings, Figure 1 is a front view in perspective showing my design, and Fig. 2 a rear view of the same.

My design consists of a bust figure of a man with spare elongated features, prominent Roman nose, mustache, and short pointed beard, wearing a high lace collar, an armor-plate, and a cross supported from the neck

by a chain. The arms, which are about half shown, are provided with puff-sleeves. This bust is formed integral with a top piece A, which joins the body B of the cane at line C. 25 The bust is formed in connection with the top piece A, so as to give the appearance that the rest of the figure or statue is concealed within the cane. Part A is circular in horizontal section, its greatest diameter being where it 30 unites with or joins the bust. The periphery of this part A is beveled, as shown.

Having thus described my invention, what I claim is—

The design for cane-heads, as shown and 35 described.

In testimony whereof I affix my signature in presence of two witnesses.

HARRY B. SNYDER.
